TELEVISION CABINET

James W. Kelso, Van Nuys, Calif., assignor to
Stromberg-Carlson Company, a corporation of
New York

Application May 7, 1952, Serial No. 19,627

Term of patent 14 years

(Cl. D56—4)

To all whom it may concern:

Be it known that I, James W. Kelso, a citizen of the United States, residing at Van Nuys, State of California, have invented a new, original, and ornamental Design for Television Cabinet, of which the following is a specification, reference being had to the accompanying drawing, forming a part hereof.

Fig. 1 is a perspective view of a television cabinet showing my new design.

Fig. 2 is a side elevational view thereof on a reduced scale.

The dominant features of my design reside in the portion shown in full solid lines.

I claim:

The ornamental design for a television cabinet, as shown and described.

JAMES W. KELSO.
